CLAIM

The ornamental design for a rechargeable battery, as shown and described.

DESCRIPTION

FIG. 1 is a perspective view of a rechargeable battery according to an aspect of the present invention; FIG. 2 is a front view of the rechargeable battery of FIG. 1; FIG. 3 is a rear view of the rechargeable battery of FIG. 1; FIG. 4 is a plan view of the rechargeable battery of FIG. 1; FIG. 5 is a bottom view of the rechargeable battery of FIG. 1; FIG. 6 is a right side view of the rechargeable battery of FIG. 1; and

1, and FIG. 7 is a left side view of the rechargeable battery of FIG. 1. A portion to which a registration is sought is drawn in solid line while the remaining portion is drawn in broken line. The alternative long and short dashed lines are lines only to show a boundary between the portion to which a protection is sought and the disclaimed portions. Thus, the alternative long and short dashed lines are not intended to represent any claimed portions.
